PACKAGING MACHINE

William W. Thompson, 3985 Race Road, Cincinnati, Ohio

Filed Apr. 13, 1961, Ser. No. 64,713

Term of patent 3½ years

(Cl. D55—1)

Fig. 4.

FIGURE 1 is a front elevational view of a packaging machine showing my new design.

FIGURE 2 is a side elevational view thereof as seen from the left side of FIGURE 1.

FIGURE 3 is a horizontal sectional view thereof taken along the line 3—3 of FIGURE 2.

FIGURE 4 is a perspective view thereof with the standard shown broken away in part for convenience of illustration.

The right angle arms are broken away in FIGURE 3 for the convenience of illustration.

The portions shown in broken lines are for illustrative purposes only.

I claim:

The ornamental design for a packaging machine, as shown and described.
